UNITED STATES PATENT OFFICE.

SAMUEL T. CRISSY, OF HACKENSACK, NEW JERSEY.

JAR-CLOSURE.

SPECIFICATION forming part of Letters Patent No. 734,047, dated July 21, 1903.

Application filed September 10, 1902. Serial No. 122,788. (No model.)

To all whom it may concern:

Be it known that I, SAMUEL T. CRISSY, a citizen of the United States, residing at Hackensack, county of Bergen, and State of New Jersey, have invented certain new and useful Improvements in Jar-Closures, of which the following is a specification, reference being had to the drawings accompanying and forming part of the same.

10 My invention pertains to means for securing a perfectly liquid and air tight closure for jars, particularly those having a large opening or mouth, such as water-coolers and the like.

15 To that end it consists, essentially, of a disk-like body carrying a gasket of rubber or other yielding material which is intended to be seated against the inside of the rim or edge of the vessel and means for expanding or pressing such gasket firmly against the rim.

20 I am aware that numerous attempts have been made to produce a tight closure by using an expansible gasket, and in some instances these have been found to a certain extent practicable; but my device embodies features of novelty and combinations of parts which I believe possess considerable advantages over the prior articles, especially when used on vessels of large size, as before mentioned. In fact, I do not know that the prior articles have been found satisfactory when used with such vessels.

25 Referring to the drawings, Figure 1 shows a vertical section of my closure. Fig. 2 is a top plan view of the expander. Fig. 3 is a section of a modification, and Fig. 4 is a section showing another form of gasket.

30 Throughout the drawings, 1 is a jar having, it will be noted, no flange or other projections at its edge except, perhaps, a slight bead as a "finish."

35 2 is a disk-like cover, usually ornamental in form and appearance and preferably of brass or other metal. The cover has near its edge a depending flange 3, while the edge itself may be turned down over the rim of the vessel, as shown. In the center of the cover is a neck 4 of a size to furnish a suitable bearing for a bolt 5, screw-threaded at its lower end and carrying a rigidly-fastened collar 6, so that the bolt may be rotated, but not vertically displaced.

The lower part of the closure 7, which may be termed the "expander," is for the sake of strength preferably slightly conical in form, 55 corrugated, as at 8, and having stiffening ribs or braces 9. At the center of the expander is a stiff plate 10, firmly fastened in any convenient way, as by solder, to give the part additional rigidity and to aid in holding in 60 place the block or neck 11, which is screw-threaded to receive the bolt 5. Near the edge is a vertical or upstanding flange 12, fitting either within the flange 3 of the cover, as shown, or without. The lower end of the 65 bolt 5 may be provided with a cap or collar to give an ornamental finish and to prevent accidental withdrawal.

Around the flanges 3 and 12, abutting against the edges of the cover and the expander, is a ring 13, constituting a gasket, which may be of rubber or other yielding material. It should be somewhat wider than the flanges, as will be readily understood.

The operation of my device will be clearly 75 seen from the foregoing. With the parts assembled as shown in Fig. 1, the closure is placed on the vessel and the bolt then screwed into the block or neck 11 by means of a key inserted in the head 14. The expander and 80 cover are thus brought together, with the result that the jacket is compressed, and consequently bulged against the wall of the vessel 1. The pressure of the gasket on the jar-wall, or, in other words, the tightness of the joint 85 at that point, is determined solely by the user, who may expand the gasket to any desired degree, as is easily understood.

The form of closure just described is of course one embodiment of my invention, 90 though the one that I regard the most convenient. The device is capable of many modifications—as, for example, those illustrated in Figs. 3 and 4. In Fig. 3 the screw-threaded part of the bolt 5 is its upper end, 95 the lower end being rotatably held in the expander by the devices shown. The square keyhole in the bolt-head may be dispensed with and a suitable handle used; but I prefer the construction shown for the reason that 100 it effectually prevents accidental loosening of the gasket, which might happen if a handle with projecting parts were employed. The flush bolt-head of Figs. 1 and 3 also ren-

ders the jar and closure more convenient for crating. In Fig. 4 I show a tubular ring used as the gasket—a form which in some cases is more convenient than a flat strip. 5 Also for the tube may be substituted a solid ring of circular cross-section or having a polygonal section of substantially equal sides. I may mention in addition that for a number of uses—as, for example, when the jar is used 10 to contain corrosive liquids—the expander may with advantage be made of glass, so that no material which is attacked by the contents of the vessel will be exposed thereto.

While I have shown and described but one 15 or two forms of my invention, it is of course understood that the same is capable of many embodiments, and I therefore do not consider myself limited to those shown; but

What I claim is—

20 1. A jar-closure comprising in combination, an upper disk-like member having a depending flange near its edge, a lower disk-like member having an upstanding flange coacting with the first-mentioned flange, a gasket 25 outside the flanges, and means for drawing the members together to expand the gasket against the wall of the jar or vessel, as set forth.

2. A jar-closure comprising in combination, an upper disk-like member having a depending flange near its edge, a lower disk-like member having an upstanding flange adapted to fit inside the first-mentioned flange to prevent lateral displacement of the disk-like members relative to each other, a gasket outside the flanges, and means for drawing the members together to expand the gasket against the wall of the jar or vessel, as set forth. 30 35

3. A jar-closure comprising in combination, an upper disk-like member having a depending flange near its edge, a lower disk-like member having an upstanding flange adapted to fit within the first-mentioned flange to prevent lateral displacement of the disk-like members relative to each other, a flexible gasket outside the flanges bearing in the angles formed by each disk-like member and its flange, and a screw-bolt for drawing the members together to expand the gasket 45 against the wall of the jar or vessel, as set forth. 50
